UNITED STATES PATENT OFFICE.

WILLIAM FRED DUNNING, OF WASHINGTON, DISTRICT OF COLUMBIA.

LOOSE-LEAF BINDER OR FILE.

1,421,677.

Specification of Letters Patent. Patented July 4, 1922.

Application filed August 24, 1920. Serial No. 405,648.

To all whom it may concern:

Be it known that I, WILLIAM FRED DUNNING, a citizen of the United States, residing at Washington, in the District of Columbia, have invented a new and useful Improvement in Loose-Leaf Binders or Files, of which the following is a specification.

My invention relates to loose leaf binders or files and more particularly to a device of 10 this character which is automatic.

In carrying out my invention I so arrange the parts thereof that when open the opposed binding posts or pins which are carried by the back will be sufficiently removed 15 from one another to enable easy access thereto so that the leaves or cards can be easily positioned upon the binding posts.

Another important feature of this invention is the provision of straight pins rather 20 than the curved ones now in use in devices of this type. I am enabled to use straight binding posts or pins because of the peculiar arrangement and construction of the back of the binder.

25 A binder constructed in accordance with my invention is practically "fool proof" inasmuch as the device cannot be locked or secured in closed position without the prongs being properly positioned to enter the aligned apertures in the cards or leaves.

Another feature of this invention is the means whereby I am enabled to secure the binder in half closed or half locked position in which position one set of the binding posts 35 or pins are positioned substantially vertically to enable the cards or leaves to be filed thereon. The binder may be thereafter completely closed, in which position the cards will be locked securely between the opposed 40 sets of binding posts.

Many other objects will be made more apparent in the specification and drawings, in which—

Figure 1 is a fragmentary perspective 45 view of a portion of the binder in half open position.

Fig. 2 is a front elevation of a portion of the binder in open position.

Fig. 3 is a vertical section taken on line 50 3—3 of Fig. 2.

Fig. 4 is a vertical transverse section with the binder in the position illustrated in Fig. 5.

Fig. 5 is a view taken on line 5—5 of 55 Fig. 4.

Fig. 6 is a vertical transverse section of the binder in closed or locked position.

Fig. 7 is a view taken on line 7—7 of Fig. 6.

Fig. 8 is a view taken on line 8—8 of Fig. 60 7, and

Fig. 9 is a fragmentary perspective view of a binding post.

In the drawings the numeral 10 represents the two covers of the binder which may be 65 constructed of any type of material embodying the proper rigidity and is here illustrated as card board.

Lying adjacent one end of each of the 70 cover pieces 10 is a binding strip 11, preferably of metal, and these metallic binding strips are adapted to be secured to the covers 10 by a fabric covering 12 thereby providing a flexible connection between the covers and these rigid metal strips 11.

The fabric extends beyond the two strips 11 and encloses a piece of stiffening material forming a semi-flexible back covering 13 which suitably encases the metallic hinge, to be more fully hereinafter described.

75 Rigidly secured to the strips 11 are post-carrying plates 14. These plates 14 are preferably fastened to the strips 11 by means of rivets 15. Formed upon the inner edges of these members 14 are bent tongues 16 forming one part of a hinge-like connection between them and the back proper of the binder which also will be more fully hereinafter described.

Extending transversely of the binder and 80 positioned through the curved lips 16 are binding rods 17. These binding rods 17 also operatively engage bent lips 18 formed upon the outer edges of a back hinge 19.

This back hinge is composed of two arc 95 shaped plates which are hingedly secured together as at 20. When the binder is in closed position these two members have a cross sectional shape which is substantially a half circle thereby providing the appearance of finished binding.

From the structure described thus far it will be apparent that the cover pieces 10 by reason of the strips 14 and the back members 19 provide a binder capable of operating in 105 a manner similar to the usual type of binders now employed.

Mounted upon the post carrying plates 14 are straight binding posts or pins 21. These posts are arranged in sets of two, the 110

sets being staggered with respect to one another to enable them to enter a series of transversely disposed apertures in the cards or leaves which they engage. By referring 5 more particularly to Fig. 9 the particular manner in which these posts are secured in place will be illustrated. The post carrying strips 14 have formed thereon binding lips 22, while the post 21 carries a recess 23. 10 The post 21 is provided with screw threads 24 to engage a screw threaded aperture in the metallic strips 11. By this construction it is obvious that the binding posts 21 may be screw-threaded into the strip 11 and 15 when they have been given a sufficient number of turns to position the recess 23 opposite the lip 22, this lip which has been previously bent back out of the path of the post 21 will be bent downwardly until it projects 20 into the recess and locks the binding post in position upon the strip 11. I have found that such a construction is particularly advantageous, but it should be understood that the binding post 21 may be secured 25 in position in any suitable manner such as by riveting or welding them to the strip 11. It is also apparent that even if the posts 21 became loose and rotated slightly, they would still be in position to enter the apertures in the cards or leaves. 30 This particular feature of the straight post is a great advantage over the curved binding posts or pins universally used in binders inasmuch as when the curved binding posts 35 become slightly rotatably displaced their outer ends are thrown out of alignment and will not enter the apertures of the cards or sheets.

The inner edges of the members 14 are 40 provided with right angular projections 25 and 26 respectively terminating in angular latch members 27 and 28 respectively. The purpose of these latches will be more fully hereinafter described.

45 Hingedly mounted upon the transverse rod 17 are link carrying members 29. At one end of the binder are a pair of links 30 pivotally secured together at one of their ends, as at 31, each link having its free 50 end pivotally mounted to the link-carrying members 29. Disposed at the other end of the binder is a pair of double links 32 pivotally secured together as at 33 having their free ends overlapping the link-carrying members 29 and pivotally secured thereto, as clearly illustrated in Fig. 1. The link-carrying members are cut away, as at 34, to accommodate the pivot 33 of these links when the binder is in closed or locked position.

60 Springs 35 having their ends secured to the link-carrying members 29, as at 36, tend to normally hold the binder in open position, as illustrated in Fig. 2.

65 Slidably mounted upon one of the link-

carrying members 29 is a latch member 37 which carries a latch 38 and terminates at its outer end in a thumb piece 39. This latch member is provided with slots 40 through which pass studs 41 to thereby slidably mount this latch member upon the member 29. A spring 42 having its ends secured respectively to the latch member and a link-carrying member 29 retains the latch member normally to the left in Fig. 75 8, or in locked position. The latch may be released by pressure inwardly upon the thumb piece 39.

Rigidly secured upon the rear face of the upper link-carrying member 29 is a stud or 80 keeper 43 adapted to engage the notch 44 of the latch 38 when the binder is in closed or locked position, as illustrated in Figs. 6, 7 and 8. The latch 38 is also provided with a beveled surface 45 which will ride past 85 the stud 43 thereby moving the latch member 37 against the tension of the spring 42. It is obvious that thereafter the latch will snap into place to engage the stud 43.

Inasmuch as the post carrying plates 14 90 are provided with angular latch members 27 and 28 these members will be locked in position by reason of the engagement of these latching members 27 and 28 with the sliding latch member 37. This locking will take 95 place, however, only when the binder is folded into horizontal position to place the latch members 27 and 28 in position to be engaged by the latch 38. This position is illustrated clearly in Fig. 5. In this position 100 the studs 21 are in their proper oppositely disposed positions and in alignment to enter the apertures in the cards or leaves. Thereafter when in locked position they will be disposed, as illustrated in Fig. 7, with the 105 binding posts engaging the apertures in the cards or sheets.

It is oftentimes desirable to arrange one set of binding posts in a substantially vertical position to facilitate the positioning of the 110 sheets or cards thereon. This particular position of the binder is illustrated in Figs. 1, 4 and 5 which figures show the lower latch 27 engaging the latch member 38. It is obvious that the engagement of the 115 latches 27 and 28 is brought about by their notched edges engaging the vertical face 46 of the latch member 38. Each of the stationary latch members 27 and 28 are provided with beveled edges which, when they 120 engage the slidable latch member 37, will move the same against the tension of spring 42 and thereafter allow the slidable latch to snap into locking position.

The cards are indicated by the letter C 125 and are dotted in several views to more clearly illustrate the operation of the binder. In Fig. 1 the binder is in what is termed "half locked" position, in which position the latch 27 carried by the lower 130

binding post plate 14 is in engagement with the straight face 46 of the latch 38 of the sliding latch member 37. With the lower strip 14 secured in this position the lower 5 binding posts 21 assume a vertical position which will thereby enable the leaves or sheets to be easily positioned upon the posts. In this view it will be noted that the other section of the binder with its cover 10, member 10 14 and binding posts 21, are raised and out of the way. If, thereafter the binder is to be locked and the cards or sheets secured in place, the upper section of the binder with the posts 21 is swung to the position illustrated 15 in Figs. 4 and 5, the member 14 carrying the upper binding posts swinging with the transverse rod 17 as a pivot. In this position the binding posts 21 are disposed parallel which will enable them to enter the 20 apertures in the cards or sheets. The latch member 28 has also been moved to a horizontal position in which position it is adapted to also engage the vertical face 46 of the latch 38. If, thereafter pressure is applied 25 vertically upon the binder to compress the springs 35, the binder will be made to assume the position illustrated in Fig. 7 in which position the notch 44 of the latch 38 engages the stud 43 carried by the upper link 30 carrying member 29 while the latch 28 engages the vertical face 46 of latch 38 in a manner similar to that of the latch 27. In this position the two sets of oppositely disposed binding posts or pins 21 are in engagement 35 with the apertures of the cards or sheets and any vertical displacement thereof is prevented by reason of the sliding latch 37 which will remain in locked position by reason of the spring 42. When the binder 40 is to be opened this may be accomplished by pressure upon the thumb piece 39 of the sliding latch member 37. This pressure will thereupon cause movement of the latch member 37 to the left, as seen in Figs. 1 and 45 4, thereby disengaging the stud 43, and also the latches 27 and 28. The springs 35 will thereupon force the back of the binder apart to the position illustrated in Figs. 2 and 3.

By forming one set of the links 32 in pairs 50 which straddle the link-carrying members 29 I am enabled to materially strengthen the back of the binder and form thereof a rigid and durable structure.

The binding pins 21 will never get out of 55 proper alignment by reason of independent rotation thereof as is quite obvious. This is a distinct advantage over the curved pins now universally in use.

It should also be noted that the two sections of the back carrying the studs or pins 60 21 cannot be locked into position unless the pins 31 are in proper alignment, inasmuch as the latches 27 and 29 are respectively rigidly secured to the members upon which the 65 pins are mounted and only when the pins 21

are in proper alignment to enter the apertures in the cards C, will the latch members be in position to be engaged by the sliding latch 38. Hence a novice cannot injure the operating parts of this device nor deface or 70 mutilate the sheets or cards by attempting to close and lock the device without the pins 21 being properly positioned in the apertures of the cards.

It is obvious that instead of the springs 35 75 and 42 I may substitute coiled, or any other type of spring.

The dimensions of this binder, may be changed to meet the varied requirements inasmuch as this invention is applicable to 80 binders of any size. The operating parts of the back may be further suitably encased if desired. Various modifications and departures from the specific form of this invention may be made without departing 85 from the spirit and scope thereof, and I particularly reserve this right.

Having thus described my invention what I claim is:

1. In a device of the class described a pair 90 of side sections, a back hingedly uniting said side sections, latches carried by said side sections, straight binding posts projecting from said side sections, and automatic means co-operating with said latches for retaining the 95 binding posts in closed position.

2. A temporary binder comprising a pair of side members, post-carrying members secured to said side members, a back hingedly connected to said post-carrying members, 100 straight binding posts projecting from said post-carrying members, angularly disposed latches projecting from said post-carrying members, and a cooperating latch adapted to engage said angularly disposed latches 105 when said binding posts are in their closed position, to retain the binding posts in their operative position.

3. A device of the class described comprising a pair of rigid side members, a spring 110 back hingedly connected to each of said side members, binding posts carried by the side members, latches carried by the side members, and a spring latch member adapted to engage the latches carried by the side members to retain the binding posts in operative 115 position.

4. A temporary binder comprising two rigid sides, binding posts carried by said side members, plates secured to said sides 120 through which said binding posts project, a back hingedly connected to said plates, springs adapted to normally force said side members apart, intermediate connecting members secured to said side plates, said 125 springs being attached to said members, a latch projecting from each plate, a slideable latch member positioned to engage both of said latches when the posts are in closed position whereby one of said sides may be 130

locked with its posts in closed position, substantially as described.

5. A temporary binder comprising two rigid sides, plates secured to said sides, binding posts passing through said plates and secured to said sides, a back hingedly engaging said plates and connecting said sides, latches carried by said plates, link-carrying members secured to said back, links pivotally engaging said link-carrying members, spring means secured to said link-carrying members for forcing said sides apart, a latch member slidably mounted on one of said link carrying members and adapted to engage said latches.

10 6. A temporary binder of the class described comprising two rigid sides, plates secured to said sides, binding posts passing through said plates and screw-threaded into said sides, tongues formed on said plates and adapted to engage recesses in said posts to

retain them in position, a back hingedly connected to said plates, link-carrying members secured to said back, two sets of links pivotally engaging said link-carrying members, one set of links being so disposed as to straddle the link-carrying members when the binder is in closed position, spring means carried by said link-carrying members tending to normally force said side members apart, a latch member slidably mounted on one of said link-carrying members, angularly projecting latches carried by said plates and adapted to be engaged by said slideable latch member when the binding posts are in closed position and a stud mounted on one link carrying member and adapted to be engaged by said sliding latch member for retaining the back in closed position against the tension of said spring means.

WILLIAM FRED DUNNING.
